BOTTLE

James L. Linn, Maumee, Ohio, assignor to Owens-Illinois,
Inc., Toledo, Ohio, a corporation of Ohio

Filed May 23, 1966, Ser. No. 2,391

Term of patent 14 years

(Cl. D58—6)

FIG. 1

FIG. 2

FIG. 3

The characteristic features of this design reside in the configuration shown in full lines on the drawing.

I claim:

The ornamental design for a bottle, substantially as shown and described.
